(57) **CLAIM**

The ornamental design for a disinfection robot, as shown and described.

DESCRIPTION

FIG. 1 is a front, top, and right side perspective view of a disinfection robot, showing our new design;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a front, top, and right side perspective view thereof, shown in a state with blinds open in use;

FIG. 9 is a front view thereof, shown in a state with blinds open in use;

FIG. 10 is a back view thereof, shown in a state with blinds open in use;

FIG. 11 is a left side view thereof, shown in a state with blinds open in use; and,

FIG. 12 is a right side view thereof, shown in a state with blinds open in use.

1 Claim, 11 Drawing Sheets
